H. M. HOBART

ELECTRICAL APPARATUS

Filed Aug. 28, 1919

Inventor:
Henry M. Hobart,
by *Albert G. Davis*
His Attorney.

UNITED STATES PATENT OFFICE.

HENRY M. HOBART, OF SCHENECTADY, NEW YORK, ASSIGNOR TO GENERAL ELECTRIC COMPANY, A CORPORATION OF NEW YORK.

ELECTRICAL APPARATUS.

Application filed August 28, 1919. Serial No. 320,479.

To all whom it may concern:

Be it known that I, HENRY M. HOBART, a citizen of the United States, residing at Schenectady, in the county of Schenectady, State of New York, have invented certain new and useful Improvements in Electrical Apparatus, of which the following is a specification.

My invention relates in a broad way to electrical apparatus of various types and to the dissipation of heat from electrical apparatus; it is particularly applicable to stationary induction apparatus such as transformers and some reactances, but is not limited thereto. One object is to provide an improved electrical apparatus. Another object of my invention is to provide an improved cooling means for electrical devices. My invention may reduce the size of and the amount of material required in a piece of apparatus designed to carry a given load or it may increase the operating efficiency of the apparatus; it may eliminate the oil heretofore required to cool, or assist in the cooling of, certain electrical apparatus, and requires less water to cool electrical apparatus of a given load capacity than water cooled transformers have heretofore required. Other objects and advantages of my invention will appear.

Since my invention is particularly applicable to transformers, I shall, for the sake of simplicity and clearness, substantially limit the further description of my invention to a transformer embodying my invention in its most complete form. The application of my invention to other types of electrical apparatus, and the application of parts only of the complete form of my invention fulfilling only part of all the objects and securing only some of the advantages of the complete form of my invention, will be readily understood therefrom.

According to a common practice prior to my invention, transformers of considerable power are submerged in oil which enters spaces left in the transformer structure for that purpose, in order that the oil may receive the heat produced in the transformer and thereby cool the same. A large transformer produces a great amount of heat during operation and this heat must be conveyed away from the apparatus to prevent its destruction. In turn the heat taken up

by the oil is absorbed by cooler water flowing through coils of pipe submerged in the oil. This practice, while necessary prior to my invention, embodies many undesirable features. Large amounts of oil are required which very greatly add to the cost of the apparatus and increase the fire hazard; and further, the use of oil limits the allowable temperature of the electrical apparatus for above something like 90 degrees centigrade (90° C.) the commonly available oils are liable to chemical changes or changes of characteristics such as the formation of solid particles which settle on the electrical apparatus submerged in the oil and restrain the escape of heat therefrom. According to the prior practice insulating materials having an organic basis are generally used within transformers; these carbonize or are destroyed or otherwise lose their insulating characteristics at sustained temperatures much above 100° C. As a result of the presence of the oil which is unable to withstand a temperature above 90° C. and the use of insulating materials that are unable to withstand a sustained temperature of much above 100° C., the amount of load transformers of the prior art may carry is more limited than would be otherwise necessary (for on the load depends the amount of heat developed and hence the ultimate temperature), and except for the limitations of these factors, a given transformer might carry a much greater load since the other materials entering into the construction of transformers may be operated at much higher temperatures without damage. This non-economic use of the copper and steel of transformers is another undesirable feature of transformers built according to the practice prior to my invention. Still a third undesirable feature of the prior practice is the amount of water required to cool the transformer by reason of the cost and difficulties involved therewith; in large cities the outlay for water is considerable, in some locations there is no convenient source of water supply, and in still other places the available water contains impurities incrusting and filling up the interior of the cooling pipes. As before indicated, by my invention it is possible to avoid any or all of these undesirable features, the oil may be eliminated, the transformer may be operated at a higher

temperature than heretofore and hence at a greater efficiency or a smaller and cheaper structure may do the work of a much larger device built according to the prior practice, 5 and in addition the amount of water required may be much reduced. For example, I anticipate that without difficulty I can provide as a substitute for a transformer of the old design requiring 1160 gallons of oil 10 to properly submerge it and 20 gallons of water per minute to cool it, a transformer embodying my invention from which the oil is eliminated altogether and the water consumption is reduced to about one quart 15 per minute.

The device of the prior practice above described is an example of "artificially cooled" electrical devices. Another example of "artificially cooled" electrical devices is 20 the air blast transformer (not submerged in oil) through which air is forced by a pump or fan for absorbing and carrying away the heat therefrom. In part my invention is a substitute for "artificially cooled" electrical devices as will appear hereinafter. "Artificially cooled" devices are distinguished from "self-cooled" devices in this, that an artificially cooled device requires the continuous operation of some 25 extraneous device or means to convey away the heat, as the constant supply of water, pumps for water or air, etc., while in self-cooled devices the heat of the apparatus goes naturally into the surrounding atmosphere 30 either from the apparatus itself directly or from the walls of the tank in which the apparatus is submerged. It is with this meaning that I hereinafter use the term "artificially cooled."

40 In a general way the transformer of my invention in its complete form, is made with inorganic or other insulating material capable of withstanding sustained temperatures of well over 105° C. without losing 45 their insulating properties, and is cooled by the evaporation of water thus taking advantage of the latent heat of evaporation or the property of water of taking up a great 50 quantity of heat during evaporation. Such 55 inorganic insulating material permits the transformers to be operated with internal temperatures running as high as 130° C. or even as high in some instances as 150° C. Pure mica, pasted mica (mica flakes pasted 60 together to form sheets, etc.), and asbestos, are inorganic insulating materials capable 65 of withstanding sustained temperatures of much over 105° C. The cooling of transformers by the evaporation of water is not limited to transformers comprising such high temperature insulations but may be applied to transformers operating at lower temperatures by a reduction of the pressure on the cooling water as by the partial evacuation 70 of the water container; in such a way

the evaporation may be made to take place so rapidly as to secure sufficient heat extraction to keep the device below 90° C.

Two factors ought to be noticed particularly: First, that the amount of heat taken up by water during evaporation is very great in comparison with the amount of heat taken up by water in nearly raising its temperature, being something like five hundred and thirty-five times the amount required to raise the same weight of water one degree centigrade in temperature; for this reason, where the conditions are favorable to evaporation it is possible to cool a given transformer by evaporation with very much less water than without evaporation as in the past. Second, that while water evaporates at every temperature at which it is possible for water to exist in a liquid state, it evaporates rather slowly at the lower temperatures, but at an exceedingly greater rate near the temperatures of 100° C.; hence while it is impracticable to cool a transformer by evaporation where the surface of the transformer operates at a temperature of considerably less than 100° C. unless some means are provided for assisting the evaporation (for too little water is evaporated to take away the heat developed), it is quite practicable to cool a transformer by evaporation without such assistance where the surface thereof is operated at 100° C. and over, which surface temperature is easily maintained by reason of the high internal operating temperature of the 100 transformer.

In the accompanying drawing and following description, I have illustrated and described in some detail, the best embodiment of my invention of which I am now aware. 105

Fig. 1 is a top plan view of a shell type transformer to which my invention is applied. Fig. 2 is a section taken on the line 2—2 in Fig. 1. Fig. 3 is a similar section of a modified form of my invention; and Fig. 4 is an explanatory diagram.

Referring now to the drawing, I have shown a shell type core 10, made up of U-shaped involute stampings or laminæ 11 which are assembled about a central bore 12 in the manner described in Letters Patent No. 952,105 issued to W. C. Fish on March 15, 1910, in order to form an annular trough or groove, as shown at 13, in which to place the windings. 115

Inasmuch as I have chosen to illustrate my invention as applied to transformers, I have shown the windings located in this trough as comprising concentrically arranged high voltage and low voltage windings 14 and 15 respectively. The top of the trough is shown as closed by a number of annular laminæ 16, split at 17 on one side in order to prevent induced or eddy currents from circulating therein. I have 120 125 130

shown insulating members 17 inserted in the gap, so formed by this splitting in order to keep the ends of the laminæ from accidentally engaging, but it will be understood by those skilled in the art that such members are by no means essential.

In order to cool the transformer just described in accordance with my invention, I employ the elongated tank 20, which has been given a generally annular form in order that it may substantially surround the core 10. The ends of the tank 20 approach each other and are preferably provided with means, here shown as the turnbuckle 21, for drawing them together in order to secure intimate contact between the walls of the tank 20 and the exterior surface of the core 10 and thereby insure good thermal conductivity for the heat generated in the transformer to the heat absorbing fluid in the tank 20. To further insure good thermal conductivity between the windings and the tank 20 and its contents, the portion of the core between the windings and the tank is made as compact as practicable as indicated in the drawing.

As heretofore remarked, the fluid here indicated at 22, in the tank 20, is preferably water on account of its large latent heat of evaporation. An inlet 23 is provided for supplying water to the tank, which inlet may also serve to drain the tank when occasion arises. An outlet 24 is also provided above the normal fluid level in order to permit the egress of steam and water vapor which arises from the surface of the water in the course of ebullition.

In operation, the transformer is operated at such load that the temperature of the windings will be well over 105° C., since the windings, as heretofore indicated, are insulated with inorganic insulating material so as to safely withstand such temperature. Thus there is maintained a relatively steep temperature gradient from the windings to the surface of the core.

Such a temperature for the windings insures a relatively high rate of evaporation of the water at the surface of the core in the tank 20 as may be readily ascertained by reference to Fig. 4, where rates of evaporation are shown as ordinates and have been plotted against temperatures taken as abscissæ. The good thermal conductivity maintained between the tank 20 and the core 10 of the transformer insures the rapid dissipation of the heat generated in the transformer. It is preferable to feed water through the inlet pipe 23 to the tank 20 during operation at substantially the same rate as that of the rate of ebullition, thus maintaining the fluid level in the tank substantially constant.

In Fig. 3 I have shown a modified form of my invention designed to secure the dissi-

pation of the heat generated in the transformer more rapidly than in the form just described.

Here the core 30 is made from involute laminæ assembled in a manner to provide an annular groove 32 for receiving the high voltage winding 33 and the lower voltage winding 34 in substantially the same manner as that described above; the top of the groove being closed by the annular laminæ 35. The core is surrounded, or substantially so, by a tank 40 of similar design to that shown at 20, which is in intimate contact with the exterior surface of core 30. In intimate contact with the interior surface of the core 30, is the cylindrical tank 41. These tanks are supplied with fluid, preferably water, in parallel from the common supply inlet 43, and also have a common exit 44 for steam and vapors generated by ebullition.

In operation, the transformer last described is operated so that the surface of its core is in the neighborhood of 100° C. and consequently the rate of ebullition of the water is here again relatively great. Since the flow of heat in this instance is in two directions, i. e. to both the inner and outer core surfaces, the heat can be dissipated with greater speed than in the form of transformer first described.

Having now described what is at present the best means known to me for carrying out embodiments of my invention, I would have it understood that such means are merely illustrative and that I do not mean to be limited thereby to the exact details shown nor in the choice of recognized equivalents except as defined in my claims hereunto appended.

What I claim as new and desire to secure by Letters Patent of the United States, is:

1. The combination with stationary induction apparatus comprising a core and windings, said windings being completely enclosed by the core and in close thermal relation therewith, of a fluid container having a wall of good thermal conductivity in close contact with an outer face of said core, whereby said windings are protected from and are in good thermal relation with the contents of said container.

2. The combination with stationary induction apparatus comprising a core and windings, of a fluid container having a wall of good thermal conductivity, said apparatus being arranged outside the container and with its core in close thermal relation with the windings and in contact with the wall of the container, whereby said windings are protected from and are in close thermal relation with the contents of said container.

3. The combination with stationary induction apparatus comprising a core and windings, of a fluid container having a wall of good thermal conductivity with its outer

surface in close contact with the outer surface of said apparatus, whereby said apparatus is protected from and is in good thermal relation with the contents of said container.

4. The combination with stationary induction apparatus comprising a core and windings, of a fluid container having a wall of good thermal conductivity with its outer 10 surface in contact with the outer surface of said apparatus, and means for drawing said surfaces tightly together, whereby said apparatus is protected from and is in good thermal relation with the contents of said 15 container.

5. The combination with electrical apparatus comprising a core and windings thereon, said core and windings being in close thermal relation and said apparatus being provided with an opening therein, of a container adapted to contain a heat absorbing fluid, said container extending into said opening in thermal relation with the walls thereof and having a portion in contact with a surface of said apparatus outside of said 25 opening.

In witness whereof, I have hereunto set my hand this 27th day of August, 1919.

HENRY M. HOBART.
